UNITED STATES PATENT OFFICE.

JOHN DAVIDSON, JR., OF MONTCLAIR, NEW JERSEY, ASSIGNOR TO AMERICAN TELEPHONE AND TELEGRAPH COMPANY, A CORPORATION OF NEW YORK.

SIGNALING-CIRCUITS FOR TOLL LINES.

1,361,024.

Specification of Letters Patent. Patented Dec. 7, 1920.

Application filed December 12, 1918. Serial No. 266,485.

To all whom it may concern:

Be it known that I, JOHN DAVIDSON, Jr., residing at Montclair, in the county of Essex and State of New Jersey, have invented certain Improvements in Signaling Circuits for Toll Lines, of which the following is a specification.

This invention relates to signaling circuits and more particularly to signaling circuits for use in connection with long distance telephone lines.

Heretofore it has been customary to provide for each toll line used for long distance connection, a signaling path to be used for supervisory and other signals necessary in connection with the establishment of such connections. In order to reduce the expense involved in such an arrangement, it has been proposed to provide a common signaling path for a plurality of lines and successively connect said common path with local signaling circuits individual to the lines at each end thereof by means of a rotary distributor or equivalent device. Arrangements of this character are disclosed in United States Patents to Bancroft Gherardi, Nos. 1,251,363 and 1,251,364 granted December 25, 1917.

One of the objects of the present invention is to improve and simplify the apparatus and system of the patents above referred to, although other and further objects of the invention will be apparent from the description hereinafter given.

These objects are accomplished by using an intermittently operating distributor for sending code signals over the common path, each toll line having a definite set of code combinations individual thereto, so that signals for a particular toll line will be transmitted by the code combinations assigned to it.

Since the intermittently operating distributor transmits one signal for each operation thereof, the invention contemplates the provision of suitable means for delaying the signals of a plurality of toll lines, which may be simultaneously in signaling condition, as well as means for determining the order in which the signals of a plurality of lines are to be transmitted. These functions are accomplished as herein disclosed by means of a normally rotating switch which is provided with a set of code contacts for each combination of each toll line

and which hunts for a set of contacts in signaling condition. As soon as its wipers make connection with such a set of contacts the switch comes to rest and transfers the combination set up to a group of relays which store up the combination and set the distributor into operation to transmit the same. The switch, in the meantime, moves on until it finds another set of contacts in signaling condition, whereupon as soon as the previous combination has been transmitted, the distributor comes to rest and the new combination is transferred to the storing relays and the operation repeated. By means of this arrangement the signals are stored up and transmitted in a definite order. It will be understood that any equivalent means for securing these results is within the scope of this invention.

In order to translate the transmitted code combinations into suitable signals for the proper toll line the invention contemplates the provision of a receiving apparatus which will respond to a particular combination to set into operation the signal for a particular line which is represented by that code combination. The receiving apparatus is herein disclosed as a pyramid relay combination of a type well known in the signaling art, but it will be understood that any suitable translating apparatus may be used for this purpose.

The invention may now be more fully understood from the following description when read in connection with the accompanying drawings, Figures 1, 2, 3 and 4 of which, when placed end to end in regular order, constitute a circuit diagram of an embodiment of the invention.

Referring to the drawing, a long distance toll line L_1 is shown extending between two distant stations, the terminal apparatus at one station being shown in Figs. 1 and 2, and the similar apparatus at the other station being shown in Figs. 2 and 4. At the originating station, the line terminates in a jack J_1 with which a plug P_1 of a toll cord T_1 is adapted to coöperate, the toll cord serving to connect the called subscriber to the toll line L_1 . At the other station the incoming end of the toll line L_1 terminates in a plug P_1' adapted to coöperate with a jack J_1' of a toll switching trunk T_1' whereby the toll line may be connected to the called subscriber. The toll cords and switching

trunks are well known in the art and are therefore, not illustrated in detail. It will be understood that a plurality of toll lines, such as L_i , will extend between the two stations, one only being shown for purposes of illustration. In order to transmit supervisory and other signals between the two stations, a signaling path P is provided which is common to a plurality of toll lines and serves to transmit the signals over all of the lines with which it is associated. At each station the signaling path P terminates in the usual bridged polar duplex set used for two-way telegraph transmission. In order 10 to transmit groups of code signals over the signaling path, a transmitting distributor TD is provided at one station and a similar distributor TD' at the other station. The transmitted code combinations are received 15 at the two stations by means of receiving distributors RD and RD' , respectively. These distributors are similar in construction to the distributors used in printing telegraphy and need not be described in 20 detail.

For the purpose of translating signals originating with the different lines into code combinations and in order to prevent the transmission of more than one signal at a 25 time, as well as to determine the order in which the signals shall be transmitted, rotating switch S , common to a group of toll lines, is associated with the signaling path P at the originating station, a similar switch S' being provided at the other station. These switches are each provided with a normally rotating brusharm, the brushes of which successively pass over sets of code contacts individual to the various lines, and 30 one brush of which passes over controlling contacts individual to the line. Each line is provided with three signal sending conductors A , B and C , each leading to a corresponding controlling contact of the switch. The switch is so arranged that as soon as its controlling wiper makes connection with a contact of a line on which a signal is waiting, the brush arm comes to rest with its code brushes contacting with the code segment corresponding to that signal. The 40 code combination thus formed is transferred to a set of relays numbered 1 to 7, inclusive, at the one station, and 1' to 7', inclusive, at the other station, whereby the combination 45 is stored up. These storing relays are associated with the transmitting distributor TD and TD' and set the same in operation to transmit the stored combination to the signaling path P . This arrangement is such 50 that three distinct signals may be transmitted in each direction for each toll line. In order to translate the received code combinations into corresponding signals and appropriate the signals to the toll lines 55 with which they originated, pyramid relay

combinations, shown in Figs. 2 and 3, are associated with the receiving distributors RD and RD' . The pyramid relays which are of a well known type are controlled by relays 11, 22, 33, 44, 55, 66 and 77, associated 70 with the receiving distributor RD and a similar set of relays associated with the distributor RD' . Each toll line is provided with two receiving signal conductors, D and E , controlled by the pyramid relays, where- 75 by the received signals are transmitted to the proper toll line. The pyramid relays are arranged to apply either ground or positive battery to the conductor E when selected, and to apply ground only to the conductor D when it is selected, thus providing for the actuation of three separate signals.

The details of the apparatus will now be clear from a description of the operation, 80 which is as follows:

Assuming that it is desired to establish a connection over the toll line L_i , the operator at the originating station will insert the plug P of the toll cord T into the jack J , completing a circuit from battery through the lamp 12 over the sleeve conductors of the plug and jack and through the winding of sleeve relay 13 to ground. Relay 13 is thereby energized, but the lamp 12 is not caused 90 to glow when connected in series with the resistance of relay 13. Relay 13, upon being energized, at its right hand front contact completes a circuit from ground through the winding of relay 14 and the right hand back 95 contact of said relay over the conductor B to the controlling segment b of the switch S . As soon as the normally rotating brusharm 15 of the switch S carries its brush 16 into connection with the contact b , a circuit is 100 completed as follows: from ground, front right hand contact of relay 13, winding and right hand back contact of relay 14, conductor B , contact b , brush 16, right hand back contact of relay 17, middle back contact of said relay, and through the right hand 105 winding of said relay to battery. Relays 14 and 17 are thereby energized and relay 14 is locked up over a circuit from ground, the front right hand contact of relay 13, winding and front right hand contact of relay 14 to battery. Relay 17 is locked up over a circuit from battery through its right hand winding, middle front contact and middle 110 winding to ground. At its left hand front 115 contact relay 17 closes a circuit over magnet 18 which stops the brusharm 15 of the switch S with its brushes 19 resting upon the code segments in the same initial plane as the controlling segment b . If the transmitting distributor TD is not at this time engaged in transmitting a code combination previously 120 set up, a circuit will be completed from ground, ring 20 of the distributor TD , over the brush of said distributor and segment 21 125 130

- thereof, over the back right hand contact of relay 23, over the conductor 24, brushes 19 of the switch S, live code segments corresponding to segment b, and in parallel 5 through the windings of storing relays 1, 2, 3, 4, 5 and 6 to battery. These storing relays are thereby energized and at their left hand front contacts complete locking circuits through their left hand windings and over 10 the conductor 25, through the winding of relay 23 and over the back contact of relay 26 to ground. Relay 23 is now energized and at its left hand front contact completes a circuit from battery over the conductor 27, over 15 the front right hand contact of relay 17 and front middle contact of said relay through its left hand winding to ground. The left hand winding of relay 17 is differentially wound with respect to its other winding so that the 20 current flowing through said winding causes the deenergization of said relay, thereby opening the circuit of the magnet 18 so that the switch S commences rotating to hunt for another signal.
- 25 In the meantime storing relays 1 to 6 inclusive, at their right hand front contacts have connected positive battery to corresponding segments in the outer ring of the distributor TD and the relay 23 at its right 30 hand front contact has completed a circuit from ground over the inner ring 20, brush and segment 21 of the distributor TD, front right hand contact of relay 23, through the winding of relay 28, over segment r, brush and ring 29 to negative battery. Relay 28 35 is now energized and completes a circuit for the start magnet 30 of the distributor TD so that the brusharm is released and is permitted to pass over the segments of the distributor. Normally the wipers of the brusharm rest upon the segment r so that a circuit is completed from positive battery, through the winding of the pole changing relay 31 of the duplex set and over segment r, brush 40 and ring 29 of the distributor to negative battery. The pole changing relay 31 is, therefore, normally energized so that negative battery is connected to the signaling path P and the polar relay 32, associated with the 45 duplex set at the distant station, is operated to hold its armature on its live contact, thereby normally maintaining the relay 39 associated with the receiving distributor RD' energized. As soon as the brush of the distributor TD passes from the segment r to the starting segment s, the circuit through the pole changing relay 31 is broken and a positive impulse is sent over the signaling path which causes the polar relay 32 to open the 50 circuit of the relay 39 at the distant station. Relay 39 upon being deenergized closes a circuit from ground, segment 34, brush and segment 35 of the receiving distributor RD', at the distant station, and over the back left 55 hand contact of relay 39 through the wind-
- ing of the start magnet 36. The brusharm of the receiving distributor RD' is now released and starts to rotate.
- In the meantime, the brusharm of the transmitting distributor TD, at the originating station begins passing over the segments 1, 2, 3, 4, 5 and 6 controlled by the relays 1, 2, 3, 4, 5 and 6, which, it will be remembered, were locked up and connected positive battery to the distributor segments, through the pole changing relay 31. As the brusharm rotates over these segments the circuit is closed from negative battery over ring 29, brush and segments 1, 2, 3, 4, 5 and 6, as the case may be, front right hand contacts of the corresponding storing relays and through the winding of the pole changing relay 31 to positive battery. Consequently a succession of six negative impulses is applied to the signaling path P by the pole changing relay 31, thereby energizing the polar relay 32 at the distant station to complete a circuit for the relay 39. At the time the brusharm of the receiving distributor RD' is passing over the segment 11' of its outer ring, a negative impulse is being received from the path P and the relay 39 is thereby energized to complete a circuit from battery over the front right hand contact of said relay, segment 37 of the distributor RD' and over the brush and segment 11' of said distributor, through the winding of relay 11'. Similarly, as the brusharm rotates over the segments 22', 33', 44', 55' and 66' circuits are completed through the windings of relays 22', 23', 44', 55' and 66'. These relays are locked up over a circuit from ground, back contact of relay 38 and through the front right hand contacts of relays 11', 22', and so forth, and through the windings of said relays to battery.
- A circuit is also completed over the front right contact of relay 11' and through the winding of the corresponding pyramid relays 40, 41, 42 and 43. A similar circuit is completed over the front right hand contact of relay 22' and through the windings of relays 45, 46, 47 and 48. A circuit is likewise completed over the contact of relay 33', through relays 49, 50, 51 and 52. Relay 44' completes a circuit through the windings of relays 53 and 54, while relay 55' completes a circuit for relay 56.
- When the arm of the transmitting distributor TD passes over the segment 7 of the outer ring no circuit is completed for the pole changing relay 31 as the relay 7 of the storing relays was not actuated. Consequently, at the time the brusharm of the receiving distributor RD' passes over the segment 7 a positive impulse is being received and the polar relay 32 opens the circuit of the relay 39 so that no circuit is completed for the relay 77.

The brusharm of the distributor TD now passes to the segment r' and at the same time completes a circuit from ground over the inner ring 20, brush and segment 57, through the winding of relay 26 to battery. Relay 26 opens a circuit of the relay 23 and the locking circuits of the storing relays which are restored to normal. The relay 28 was deenergized as soon as the brusharm passed from the contact 21, so that the circuit of the start magnet was opened and as soon as the brusharm passes from the segment 57 to the segment 21 it engages with the catch controlled by the start magnet and comes to rest. The transmitting distributor TD is now ready to transmit a new signal as soon as a new combination is set up.

Returning again to the receiving distributor RD', the brusharm thereof in passing from the segment 77' to the segment 57 closes, momentarily, a circuit from ground, back left hand contact of relay 77, segment 58, brush and segment 57 of the distributor RD', front left hand contact of relay 66', front right hand contact of relay 56, front left hand contact of relay 53, front right hand contact of relay 50, front right hand contact of relay 46 and front right hand contact of relay 41 to the conductor E, over said conductor, over upper back contact of relay 59 and through the lower winding of said relay to battery. Relay 59 is energized over this circuit and a locking circuit is completed from battery through its lower winding, upper front contact, through its middle winding to ground. At its middle front contact relay 59 closes a circuit from ground over the lower back contact of relay 60 and through the guard lamp 61 to battery. The guard lamp 61 now glows to indicate to the toll operator that the originating operator has connected a calling line to the toll line L_1 and that the connection should now be completed to the called subscriber.

The brusharm of the distributor RD' has, in the meantime, passed from segment 57 to segment 62, thereby completing a circuit from ground segment 34, brusharm and segment 62 of the distributor and through the winding of clear out relay 38 to battery. Relay 38 upon being energized opens a locking circuit for the relay 11', 22', and so forth, which are thereby restored to normal. These relays upon deenergizing open the circuits of the pyramid relays, which are also restored to normal. The receiving arrangement is now in condition to receive another signal.

The operator, upon observing that the lamp 61 is glowing, inserts a plug P' into a jack J_1' of a toll switching trunk T_1' , whereby the call may be completed to the desired line. This operation completes a circuit for

the sleeve relay 63 of the trunk, which completes a circuit for the relay 60. Relay 60, at its lower front contact, opens the circuit of the guard lamp 61 which is now extinguished. At its middle front contact relay 70 completes a circuit from ground over the lower back contact of relay 64 and lower back contact of relay 65, through the winding of relay 67 and over the back contact of said relay to the signaling conductor A, thereby placing a ground potential upon the segment a of the switch S' . As soon as the brusharm 68 of the switch S' carries its wiper 69 into connection with the segment a , a circuit is completed over the circuit previously traced to the segment a , over the brush 69, back left hand contact of relay 70, back middle contact of said relay, through the left hand winding of said relay to battery. Relays 67 and 70 are energized, relay 67 being locked up over its front contact and relay 70 being locked up over its middle front contact and through its middle winding to ground. Relay 70 completes a circuit of a magnet 71, which stops the brusharm with its brushes 72 resting upon the code segments in the same radial plane as the segment a . A circuit is now completed from ground over inner ring 73, brusharm and segment 74 of distributor TD', over the back left hand contact of relay 75, over conductor 76, brushes 72 and the segments upon which they rest, and thence through the left hand windings of relays 1', 2', 3', 4', 5' and 6' to battery. These relays upon being energized are locked up in series with relay 75, which is thereby energized and its front right hand contact completes a circuit from battery over conductor 78, front left hand contact of relay 70, front middle contact of said relay and through the right hand winding of said relay to ground. Relay 70 being differentially wound is deenergized by the circuit thus closed and opens the circuit of magnet 71, thereby permitting the switch S' to begin hunting for another signal.

Relay 75 at its left hand front contact completes a circuit from ground over the inner ring 73, brush and segment 74 of the distributor TD', over the front left hand contact of relay 75, through the winding of relay 79, over segment r' , brush and ring 80 of the distributor to negative battery. Relay 79 is energized and closes a circuit for the start magnet 81, which releases the brusharm of the distributor TD'. The brusharm in passing from segment r' to s' opens a circuit of the pole changing relay 82, which thereupon sends a positive impulse over the signaling path P , causing the polarized relay 83 to open the circuit of relay 84, which in turn completes the circuit of the start magnet 85 of the receiving distributor RD at the originating station. The brusharm of said distributor is now

- released and rotates over the segments 11, 22, 33, and so forth at the same time that the brusharm of the transmitting distributor TD' rotates over the segments 1', 2', 3', 4', and so forth. As the brusharm of the distributor TD' rotates impulses are sent through the pole changing relay 82 for each segment except 7'. Consequently, the pole changing relay 82 transmits over the path 10 P, a code combination consisting of six negative impulses followed by one positive impulse. The polar relay 83 therefore closes the circuit of relay 84 six times as the brusharm of the receiving distributor RD passes over the segments 11, 22, 33, 44, 55 and 66, thereby completing circuits for the relays 11, 22, 33, 44, 55 and 66. The transmitting distributor TD' now passes on to the segment 7', causing the pole changing relay 82 to transmit a final negative impulse over the signal path P, which energizes the polar relay 83 to finally close the circuit of the relay 84, which holds open the circuit of the starting magnet 85. The brusharm of the transmitting distributor TD' now engages with the catch controlled by the start magnet 81 and comes to rest.
- The relays 11, 22, 33, 44, 55 and 66 are locked up over their front contacts and over the back contact of relay 86 and complete circuits for pyramid relays 87 to 101 inclusive. As the brusharm of the distributor RD passes from segment 77 to segment 102, a circuit is completed from ground over the back right hand contact of relay 77, segment 103, brush and segment 102 of the distributor RD, front right hand contact of relay 66, left hand front contact of relay 101, right hand front contact of relay 99, left hand front contact of relay 96, left hand front contacts of relays 92 and 88 to the conductor E and over said conductor, through the winding of marginal relay 104 and through the winding of relay 105 to negative battery. Relay 104 is not energized by the current supplied from a single battery, but requires two batteries in series in order that it shall attract its armature and hence is not energized by the circuit above traced.
- Relay 105 upon being energized attracts its armatures but no effect is produced thereby as a connection is merely completed from negative battery through a resistance and over the front right hand contact of relay 105, right hand back contact of relay 106, through the left hand winding of said relay to the negative pole of the battery. It will be seen therefore, that the signal thus transmitted is without any effect at this time.
- The transmission of this particular code combination, under different circumstances, as will be later pointed out, results in a flashing operation of the lamp 12 to indicate that the line is busy or that the called subscriber is flashing his switch hook.
- Returning again to the connection completed over the toll switching trunk T₁', as soon as said connection has been completed by a B operator to the jack of the called line, the called subscriber's receiver being still on his switch hook, battery is bridged across the talking conductors of the toll switching trunk in a manner well known in the art. As soon as battery is thus bridged across the trunk, the lower winding of relay 76 64, which is included in the talking circuit, receives current and said relay is energized. The energization of relay 64 completes a circuit from ground over the middle front contact of relay 60, over the lower front contact of relay 64 and through the winding of slow release relay 65 to battery. Relay 65 upon being energized, at its lower contact opens the locking circuit of relay 67, which is now restored to normal. 85
- Relay 65 at its upper contact closes a circuit over the lower back contact of relay 107, through the winding of relay 108 and the back contact of said relay to conductor B, thereby applying ground potential to the segment b of the switch S'. As soon as the brush 69 of the brush arm 68 of the switch S' rests upon the segment b, the relay 70 is energized as before to complete a circuit for the magnet 71, which stops the switch 95 with its brush 72 resting upon the code segments corresponding to the segment b. This completes a circuit for relays 1', 2', 3', 4' and 5', which are locked up and set the distributor TD' into operation, as before, to 100 transmit the resulting code combination. A code of five negative impulses and two positive impulses is now transmitted and the receiving distributor RD is released, and as it rotates actuates relays 11, 22, 33, 44 and 55. These relays in locking up actuate the corresponding pyramid relays.
- As the brusharm of the distributor RD passes over segments 102 and 103 a momentary impulse is sent from ground over the back contact of relay 77, segment 103, brush and segment 102 of the distributor, back contact of relay 66, front contacts of relays 101, 100, 97, 93 and 89, over the conductor D and over the back right hand contact of relay 106 and the left hand winding of said relay to negative battery. Relay 106 is energized and locked up by a circuit from negative battery, through its left hand winding, right hand front contact and middle winding to ground. At its middle contact relay 106 closes a circuit in shunt of the winding of the sleeve relay 13 through a resistance 108 and over the middle contact of relay 106 to ground. The lamp 12 is now 110 caused to glow, thereby indicating to the toll operator at the originating station that the connection has been completed to the called subscriber's line and that the subscriber should now be rung.

The operator, in response to this signal, applies ringing current over the plug P_1 and the jack J , energizing the ringing relay 109. This completes a circuit from ground over the left hand front contact of relay 14, (which relay, it will be remembered was previously locked up) over the lower front contact of relay 109, back right hand contact of relay 110, left hand back contact of said relay and through the right hand winding of said relay to battery. Relay 110 is energized and locked up through its right hand and middle windings in series. A circuit is now completed from ground through the left hand winding of relay 110, left hand front contact of said relay, right hand front contact of said relay to the conductor A, thereby connecting ground potential to the segment a of the switch S' . As soon as the brush 16 of the brusharm of said switch makes connection with said segment, a circuit is established for the relay 17, which brings the switch to rest in the manner already described, with the brushes 19 contacting with the live code segments corresponding to segment a . This completes the circuits for relays 1, 2, 3, 4, and 5, which are locked up and set the distributor TD into operation to transmit a code signal of five negative and two positive impulses. The receiving distributor RD' is released and in response to the five negative impulses completes circuits for relays 11', 22', 33', 44' and 55'. These relays in turn energize the corresponding pyramid relays so as the brusharm passes over segments 57 and 58 a circuit is completed from ground, over the back contact of relay 77', over segments 58 and 57, over the back contact of relay 66', front left hand contact of relay 56, front right hand contact of relay 54, front left hand contact of relays 54, 47 and 42 and over the conductor D, through the winding of slow release relay 111 to battery. Relay 111 is now energized and completes a circuit from ground over its lower front contact, lower front contact of relay 59, (which, it will be remembered, was previously locked up) and through the winding of slow release ringing relay 112 to battery. Relay 112 now applies ringing current to the called line and at its upper front contact closes a circuit through the upper winding of relay 64 to maintain said relay energized while ringing current is applied.

When the called subscriber responds by moving his receiver from the switch hook, the battery which had been bridged across the talking conductors of the toll switching trunk T_1 , is automatically removed in a manner well understood in the art, thereby deenergizing the relay 64 which in turn opens a circuit of the relay 65. A circuit is now completed from ground over the middle

front contact of relay 60, lower back contacts of relays 64 and 65, through the winding of relay 67, over the back contact of said relay to the conductor A, thereby applying ground potential to the segment a of the switch S' . As soon as the brusharm comes to rest upon this segment, circuits are completed over the corresponding code segments for relays 1', 2', 3', 4', 5' and 6', which are locked up and set the distributor TD' into operation to transmit a code combination of six negative impulses and one positive impulse over the signaling path P .

The receiving distributor RD at the originating station is released and in response to the six negative impulses completes circuits for relays 11, 22, 33, 44, 55 and 66, which are locked up and complete circuits as before for the corresponding pyramid relays. When the brusharm of the distributor RD passes over segments 102 and 103 a circuit is completed from ground over the back contact of relay 77, segments 102 and 103, front right hand contact of relay 66, front left hand contact of relay 101, front right hand contact of relay 99 and front left hand contacts of relays 96, 92 and 88 to the conductor E, through marginal relay 104 and through the winding of relay 105. Relay 104 is not energized, but relay 105 is energized and completes a circuit from negative battery over its front right hand contact and the front right hand contact of relay 106, which had been previously locked, and through the right hand differential winding of said relay to ground. Relay 106 is thereby deenergized and at its middle contact opens the shunt through the resistance 108, thereby causing the lamp 12 to be extinguished, indicating to the toll operator that the called subscriber has responded.

Should the called subscriber desire to call the attention of the originating operator by flashing his switch-hook, the relay 64 would be energized and deenergized as the switch-hook is moved up and down. The relay 64 upon being first energized would complete the circuit of slow release relay 65 which will remain energized during the subsequent deenergization of the relay 64. Consequently, a series of momentary impulses are transmitted from ground over the front contact of relay 60, lower back contact of relay 64, lower front contact of relay 65, through the winding of relay 107 to battery. Relay 107 is slow releasing and remains energized while receiving these impulses. Said relay at its lower contact holds open the circuit of relay 108 and at its upper front contact connects ground to the conductor C, thereby applying ground potential to the segment c of the switch S' . The switch arm now comes to rest with its brushes 72 upon the

code segment corresponding to segment *c*, thereby completing the circuit of relay 7', in addition to the relays 1', 2', 3', 4', 5' and 6', which, it will be remembered, were energized when the brusharm rested upon the segment *m*. These relays are now energized and cause the transmitting distributor TD' to transmit a code combination of seven negative impulses over the signaling path 10 P, which cause the receiving distributor RD to transmit impulses to relays 11, 22, 33, 44, 55, 66 and 77. These relays are locked up and complete the circuits of the pyramid relays.

15 As the brusharm passes over segments 102 and 103, relay 77 being now energized, a circuit is completed from positive battery instead of from ground, over the front right hand contact of relay 77, over segments 103 and 102, front right hand contact of relay 66, front left hand contact of relay 101, right hand contact of relay 99, front left hand contact of relays 96, 92 and 88, and thence over the conductor E, through the marginal relay 104 and through the relay 105 to negative battery. Relay 104 being now included in a circuit with two batteries in series, energized as is relay 105. Relay 105 at its right hand front contact applies negative battery over the right hand front contact and through the right hand differential winding of relay 106, thereby deenergizing said relay. Relay 104 at its front contact completes a circuit from battery through the winding of relay 112 to ground. Relays 104 and 105 are deenergized as soon as the impulse from the receiving distributor ceases and a locking circuit is then completed for relay 112, from ground through 40 its winding, left hand back contact of relays 105 and 106 and over the left hand front contact of relay 13 to battery. Relay 112 closes a circuit from ground through an interrupter 115 and over the front contact 45 of relay 112, back middle contact of relay 106 and through the resistance 108 to the sleeve circuit, thereby shunting the sleeve relay 13 and causing the lamp 12 to flash. The originating operator upon observing the 50 flashing of the lamp 12 may then listen in and respond to the signal of the called operator.

As soon as the called subscriber ceases to flash his switch hook, the relay 64 deenergizes and remains deenergized thereby opening the circuit of relay 65 so that ground is again connected through the winding of relay 67 to the conductor A and six negative impulses are again transmitted over the 55 signaling path P to the receiving distributor RD. The distributor functions as before described to complete a circuit from ground over the conductor E and through the marginal relay 104 and through the winding of

relay 105 to negative battery. Relay 105 65 upon being energized opens a locking circuit of relay 112, thereby deenergizing said relay, which in turn opens the interrupted circuit previously traced so that the lamp 12 is extinguished. 70

Returning again to the establishment of the connection with the called subscriber, it will be remembered that the incoming operator in response to the guard lamp 61 inserted the plug P₁ in the jack J₁ of the toll switching trunk T₁ so that a B operator could complete the connection with the called subscriber. In case the B operator should find the called subscriber's line busy she would then connect the toll switching trunk 80 T₁ to a busy back interrupting circuit whereby the same effect would have been produced as when the called subscriber flashed his switch hook as just described. In other words, battery would be intermittently 85 bridged across the toll switching trunk and the relay 64 would be intermittently energized and deenergized. This would result in the continuous energization of the relay 107, as before described, thereby applying 90 ground to conductor C so that seven negative impulses would be transmitted over the signaling path P and at the receiving distributor RD positive battery would be connected to the conductor E, to energize 95 marginal relays 104 and 105. This results in the intermittent shunting of the relay 13 through the resistance 108, thereby causing the lamp 12 to flash, indicating to the originating toll operator, who has not yet received any ringing signal, that the line is 100 busy.

When, at the close of the conversation, the originating toll operator receives a disconnect signal from the called subscriber, the 105 plug P₁ will be withdrawn from the jack J₁ thereby releasing the relay 13. Relay 13 at its back left hand contact connects ground through the winding of relay 113 and over the back contact of said relay to 110 the conductor C, thereby applying ground to the segment *c*. The switch arm S now comes to rest on this segment thereby completing circuits through the storing relays 1 to 7 inclusive. In this instance, it will 115 be noted, that the relay 7 is energized as well as the other relays. Consequently, the last impulse transmitted by the distributor TD over the signaling path P will be negative so that at the receiving station of Fig. 3, relay 77 will be energized as well as the other relays. Accordingly, when the brusharm of the receiving distributor RD' passes over the segments 57 and 58 a circuit is completed from negative battery instead of from ground and over the front left hand contact of relay 77', segments 58 and 57, front left hand contact of relay 66', front right hand

contact of relay 56, front left hand contact of relay 53, front right hand contact of relays 50, 46 and 41 to the conductor E, over said conductor, and over the upper front contact 5 of relay 59, through the differential winding of said relay to ground. Relay 59 is thereby deenergized and at its back middle contact completes a circuit from ground over the lower front contact of relay 60 and through 10 the lamp 61, thereby indicating to the operator that the connection should be taken down. Upon withdrawing the plug P_1 from the pack J_1 the relay 60 will be deenergized and the circuits will be restored to 15 normal.

It will be seen that by means of this invention a large number of long distance toll lines may have the signals incidental to the establishment of a connection transmitted 20 over the same signaling path without interference. As illustrated, the signaling path will serve for twenty-eight toll lines since the pyramid circuits will complete twenty-eight different pairs of circuits corresponding 25 to conductors D and E. This number may be increased to thirty-two by providing relays 52, 48 and 43 with the same number of contacts as relays 51, 47 and 42. It will be understood, of course, that the capacity of 30 the system may be increased or decreased by increasing or decreasing the number of relays, such as 11', 22', and so forth.

It will be further understood, with reference to the pyramid circuit, that while for 35 purposes of illustration certain of the relays are shown as having a large number of contacts, in practice it may be more expedient to provide a large number of relays each having a smaller number of contacts.

40 In general, it will be obvious that the principles herein disclosed may be embodied in many other organizations different from that illustrated without departing from the spirit of the invention as described in the following 45 claims.

What is claimed is:

1. In a signaling system, a transmission, 50 circuit extending between two stations, a signaling path extending between said stations, means responsive to a change in the condition of said transmission circuit to transmit a code combination over said signaling path and means to translate the received code combination into a signal individual to said 55 transmission circuit.

2. In a signaling system, a plurality of transmission circuits extending between two stations, a signaling path common to said circuits and extending between said stations, 60 means responsive to a change in the condition of one of said circuits to transmit a code combination characteristic of said circuit over said path and means to translate the received code combination into a signal individual to said transmission circuit.

3. In a signaling system, a transmission circuit extending between two stations, a signaling path extending between said stations, means associated with said transmission circuit at one of said stations for originating a signal, means responsive to the origination of said signal to transmit a code combination over said path to the other station, and means at the other station to translate said code combination into a signal for 70 said transmission circuit.

4. In a signaling system, a plurality of transmission circuits extending between two stations, a signaling path common to said circuits and extending between said stations, 80 means associated with each of said transmission circuits at one of said stations for originating signals, means responsive to the origination of a signal for transmitting a characteristic code combination over said path 85 to the other station, and means at the other station to translate said code combination into a signal for the corresponding transmission circuit.

5. In a signaling system, a transmission 90 circuit extending between two stations, a signaling path extending between said stations, means associated with said transmission circuit at one of said stations for originating a signal, means for storing said signal, means for translating said signal into a code combination and for transmitting said combination over said signaling path to the other station, means for receiving the transmitted code combination and for retranslating 95 said combination into a signal for said transmission circuit.

6. In a signaling system, a plurality of transmission circuits extending between two stations, a signaling path common to said 105 transmission circuits and extending between said stations, means associated with each of said circuits at one of said stations for originating a signal, means for storing said signals, means for successively translating the 110 stored signals into characteristic code combinations, means for successively transmitting said combinations over the common signaling path to the other station, means for receiving the transmitted combinations, 115 and means for retranslating the received combinations into signals appropriate to the transmission circuits with which they originated.

7. In a signaling system, a transmission 120 circuit extending between two stations, a signaling path extending between said stations, means associated with said transmission circuit at one of said stations for originating a plurality of signals, means responsive to the origination of a signal for storing said signal, means to translate the stored signals into characteristic code combinations, means to successively transmit said combinations over 125 said signaling path to the other station, 130

- means for receiving the transmitted combinations, and means for retranslating the received combinations into signals for said transmission circuit.
5. 8. In a signaling system, a plurality of transmission circuits extending between two stations, a signaling path common to said transmission circuits and extending between said stations, means associated with each of said transmission circuits at one of said stations for originating a plurality of signals for each circuit, means for storing said signals, means for successively translating the stored signals into characteristic code combinations, means for successively transmitting said combinations over the common signaling path to the other station, means for receiving the transmitted combinations, and means for retranslating the received combinations into a plurality of signals appropriate to the transmission circuits with which they originated.
9. In a signaling system, a plurality of transmission circuits extending between two stations, a signaling path common to said transmission circuits extending between two stations, means associated with each of said transmission circuits at one of said stations for originating signals, an automatic switch for storing said signals, translating them into characteristic code combinations and for determining the order in which they will be transmitted, means to transmit said code combinations over said signaling path to the other station and means for retranslating the received combinations into signals appropriate to the transmission circuits with which they originated.
10. In a signaling system, a plurality of transmission circuits extending between two stations, a signaling path common to said circuits and extending between said stations, means associated with each of said transmission circuits at one of said stations for originating signals, an automatic switch having a set of contacts corresponding to a signal for each transmission circuit, each set including code determining contacts, means responsive to the origination of a signal by one of said transmission circuits for causing said switch to complete circuits over said code determining contacts, means to transmit over said signaling path the code combination thus determined, and means to translate the transmitted combination into a signal appropriate to the transmission circuit with which it originated.
11. In a signaling system, a plurality of transmission circuits extending between two stations, a signaling path common to said transmission circuits and extending between said stations, means associated with each of said transmission lines at one of said stations for originating signals, and an intermittently operating distributor for transmitting signals originating with any of said transmission circuits over said signaling path to the second station.
12. In a signaling system, a plurality of transmission circuits extending between two stations, a signaling path common to said transmission circuits and extending between said stations, means associated with each of said transmission lines at one of said stations for originating signals, means for transmitting signals originating with any of said lines over said signaling path to the other station, and an intermittently operating distributor at said other station for appropriating the transmitted signals to the transmission circuit with which they originated.
13. In a signaling system, a transmission circuit extending between two stations, a signaling path extending between said stations, means to apply ringing current to said circuit at one of said stations, means responsive to the application of ringing current to said circuit to transmit a code combination over said signaling path to the second station, and means responsive to said code combination to apply ringing current to a portion of said transmission circuit at said second station.
14. In a signaling system, a plurality of transmission circuits extending between two stations, a signaling path common to said transmission circuits and extending between said stations, means to apply ringing current to said circuits at one of said stations, means responsive to the application of ringing current to said circuits to successively transmit code combinations over said signaling path to the second station, and means responsive to said code combinations to apply ringing current to said transmission circuits at said second station.

In testimony whereof I have signed my name to this specification this 9th day of December, 1918.

JOHN DAVIDSON, JR.
